Lancaster and Allwine

UNITED STATES PATENT OFFICE.

GEORGE F. FERRIS, OF GRAND FORKS, NORTH DAKOTA.

VALVE-GRINDING TOOL.

Application filed February 18, 1922. Serial No. 537,575.

To all whom it may concern:

Be it known that I, GEORGE F. FERRIS, a citizen of the United States, residing at Grand Forks, in the county of Grand Forks 5 and State of North Dakota, have invented certain new and useful Improvements in Valve-Grinding Tools, of which the following is a specification.

This invention relates to improvements 10 in valve grinding tools.

The primary object of the invention is the provision of a valve grinding tool adapted for specific use in connection with the poppet valves and their seats, of internal combustion engines, in order to provide an accurate surface engagement between the valve and its seat.

An important object of the invention is the provision of a valve grinding tool 20 which is so constructed as to permit oscillative rotations of the valve in different directions for different degrees of angular travel.

A further object of the invention is the provision of an improved valve grinding tool, preferably for manual operation, including a novel operating shaft and hand operating mechanism reciprocable thereon, whereby rotation of the shaft may be effected in positive manner to oscillate the 25 same in forward and reverse directions.

Other objects and advantages will be apparent during the course of the following detailed description.

In the drawing, wherein similar reference characters designate corresponding parts throughout the several views,

Figure 1 is a cross sectional view of the improved valve grinding tool showing co-40 operating details thereof.

Figure 2 is a transverse cross sectional view taken on the line 2-2 of Figure 1.

Figure 3 is a cross sectional view taken on the line 3-3 of Figure 1.

Figure 4 is a cross sectional view taken on the line 4-4 of Figure 1.

Figures 5 and 6 are diagrammatic illustrations of a detail of the improved valve grinding tool, showing the same in a developed form,

Figure 7 is a side elevation of a detail of the improved valve grinding tool.

Figure 8 is a cross section of the detail illustrated in Figure 7.

In the drawing, wherein for the purpose 55 of illustration is shown a preferred embodiment of my invention, the letter A designates the improved valve grinding tool including the supporting body portion B, and operating mechanism C reciprocably mounted thereon.

It is accepted practice in grinding of valves that the same be frictionally ground upon its seat, by alternately rotating the same in different directions over paths of 60 varying angular travel. This relative movement of the abutting surfaces of the valve member and its seat tends to eradicate irregularities and pits found therein incident to continuous operation of the valve. The 65 improved valve grinding tool, which will be hereinafter described in detail, embodies this principle of valve grinding, which is the most accurate and correct and requires that the most active grinding rotary movement of angular travel of the valve member upon its seat be less than the reverse rotary movement. The improved valve grinding tool effects this difference in travel in a 70 novel and positive manner.

The body supporting portion B of the improved valve grinding tool A preferably comprises a shaft 11, hand engaging portion 12; and article engaging or bit apparatus 13. The shaft 11 is preferably of a high grade 75 of steel and provided with a pair of grooves 14 and 15 spirally formed therein, from the upper shoulder 16 provided upon the shaft 11 by a reduced shank portion 17 extending axially upward therefrom. The 80 grooves 14 and 15 while spiralled in the same general direction circumferentially of the shaft 11 are of different pitch, the groove 14 preferably defining the groove of greatest pitch.

The hand engaging portion 12 of the tool body B, is preferably mounted upon the reduced shank 17 of the shaft 11, including the ball bearing cup 19 seated upon the shoulder 16 and receiving a plurality of 100

anti-friction elements 20 therein. A bearing piece 21 is provided about the shank portion 17 having the lower reduced end 22 thereof resting against a washer 23, which 5 is disposed immediately within the cup 19 and upon the anti-friction elements 20 therein. The upper end 24 of the bearing part 21 is flanged, and counter-sunk in the hand grip 25; being detachably secured thereto as by 10 screw elements 26. It is preferred, that a nut 27 be provided upon the upper edge of the reduced shank 17 and in screw threaded engagement therewith, whereby the bearing portion 21 is secured to the shaft 11. 15 The hand engaging head 25 is recessed as at 29 to receive the adjusting nut 27. Thus, when an operator grasps the hand engaging head 25, the shaft 11 may easily rotate, notwithstanding a firm grip by the operator upon 20 the swivel portion 12 of the improved tool.

The article engaging end 13 of the tool portion B preferably comprises a shank 30 having a reduced upwardly extending screw threaded end 31 thereon for adjustment in 25 a socket 32 extending inwardly in axial manner upon the lower end of the shaft 11. This shank portion 30 is provided in several different lengths, which may be selectively used to conform to the valve arrangement 30 which it is desired to grind. It is preferred that the lower end of the shank 30 be axially slotted inwardly, whereby a reversible valve engaging blade or element 34 may be inserted therein, and retained in firm position by 35 a cotter pin 35 extending transversely through the bifurcated end of the shank 30. Various valves are provided with different types of bit engaging sockets. One type is provided with the screw head slot, while 40 another type is provided with spanner sockets. Thus, it is desired that one end 36 of the valve engaging member 34 be of chisel blade formation tapering outwardly to a dull edge. The opposite end of the reversible 45 valve engaging member 34 may be provided with the depending lugs 37, in spanner wrench formation.

The operating mechanism C is preferably provided for cooperation with the grooves 50 14 and 15 of the shaft 11, in order to effect the variable angular rotations of the latter, in a manner which will now be described in detail. A casing 40 is provided as a part of the mechanism C having the outer surface 55 41 thereof suitably shaped to conform to the palm of a user's hand. The interior 42 of the casing 40 is axially recessed in such manner as to provide for the reception of a clutch mechanism 43 in the upper end of 60 the casing 40, facing the hand engaging swivel head 12, and a clutch mechanism 44 in the lower end of the casing 41, and facing toward the bit end 13 of the tool A. The clutch mechanisms 43 and 44 are provided 65 for respective cooperation in the slots 14

and 15 of the shaft 11, so that a downward movement of the operating mechanism C upon the shaft 11 will effect a rotation of the shaft 11, say to the left; and the upward sliding of the operating mechanism B upon the shaft 11 effecting a right hand rotation of the shaft 11, travelling over a greater angular distance than that which the same travels for downward sliding of the operating mechanism C. 75

Each of the clutch mechanisms 43 and 44 is provided with a jaw portion 45 secured as by screw elements 46 to the outer ends of the casing 40 so that an annular series of teeth 48 extends inwardly of the passage way 42 in the casing 40. As can readily be seen from Figure 1 of the drawing, the teeth 48 of the clutch device 43 extend downwardly into the casing 41, and in contradistinction to the teeth 48 of the clutch mechanism 44 which extend upwardly into said casing. A sliding member 49 is provided as a part of each clutch mechanism 43 and 44, and including a sleeve 50 having teeth 51 annularly formed upon an end thereof and adapted for cooperation with the series of teeth 48 above described. It is preferred that these portions 49 of the clutch mechanism which may be appropriately termed movable jaws, are slidably mounted upon the shaft 11, and relatively movable within the casing 40 so that the clutch mechanisms 43 and 44 may be selectively locked to effect a desired rotation of the shaft 11. In order to effect an accurate working of the mechanism within the operating device C, it is preferred that the sliding jaws 49 be maintained in engagement with the shaft 11 with a certain amount of friction. To this end, spring arms 52 and 53 have been provided, extending from a reduced portion 54 of the sleeve 50, and having segmental shaft gripping shoes 56 upon their free ends, concavely facing in ring like manner. The circumferential flange 57 is provided as a part of each of the sliding jaws 49, circumferentially extending from the sleeve portion 50, and in the case of the clutch mechanism 43 and 44, said flanges being provided for engagement against shoulders 58 and 60 formed inwardly from the upper and lower ends respectively of the casing 40. 110

It is preferred that the sleeve portions 50 and 54 of the sliding jaw 49 of the upper clutch mechanism 43 have a pair of pins 61 therein, which extend into the groove 14 in shaft 11. Similarly, the lower sliding jaw 49 of the clutch mechanism 44 is provided with a pair of pins 62, which extend into 115 the spiral groove 15 of the shaft 11. 120

In operating the device, the user generally grasps the head mechanism 12 of the improved tool A in the right hand, and engages the operating mechanism C in the 125 130

other hand. Assuming the reciprocating mechanism C to be upon the upper end of the shaft 11, adjacent the swivel portion 12 thereof, as is illustrated in Figure 1, by a 5 downward movement of the same upon the shaft 11, the clutch mechanism 43 will become locked, by reason of the fact that the teeth 48 of the fixed jaw portion 45 will engage the teeth 51 of the sliding portion 49 thereof, thus preventing the relative rotation of the jaw portions 45 and 49 of said clutch mechanism 43. The resultant effect 10 of a downward movement of the operating device C will be to impart a rotary movement to the shaft 11, as defined by cooperation of the pins 61 in the shaft groove 14. This downward movement of the mechanism C will likewise cause a release of the jaws 45 and 49 forming the lower clutch mechanism 15 44. This operation is obvious, since as above described, the sliding jaw 49 is maintained in engagement with the shaft 11 with more or less friction, and as downward movement is imparted to the device C, the casing 40 20 will move relative to the sliding portion of said lower clutch mechanism 44 until the flange 57 engages the lower shoulder 60. As can readily be seen from Figure 1 of the drawings, this operation will cause a release 25 of the jaws 45 and 49 of the lower clutch mechanism 44, and during downward movement of the operating mechanism C, the jaw portion 49 will rotate within the casing 40.

During upward movement of the operating mechanism C, the clutch mechanism 43 is automatically unlocked and the lower clutch mechanism 44 becomes locked. This is readily obvious, and the jaw portions 45 and 49 of the lower clutch mechanism 44 being in engagement, and the pins 62 of said lower clutch mechanism 44 engaging in the groove 15 will cause a rotation of the shaft 11, directly opposite to the rotary movement of said shaft 11 during downward movement of said mechanism C.

Various ratios between the grooves 14 and 50 15 can of course, be provided upon the shaft 11. For practical purposes, it has been found that the groove 14 may be spiralled upon the shaft 11 so as to be positioned thereon for one complete circumference about the shaft 11 in twelve inches of the same extending longitudinally of said shaft 11. On the other hand, the groove 15 is less steep than the groove 14 and is spirally positioned upon the shaft 11 for one complete circumference in eight inches of the same extending longitudinally of the shaft 11. Thus, the grooves 55 14 and 15 bear a fixed ratio to each other of one to one and a half.

The operating mechanism C has a defined path of linear travel axially of the shaft 11, being limited upwardly of the shaft 11 by engagement of the top of the upper jaw 45 60 against the lower surface of the ball bearing

cup 19; and limited in its downward movement by the engagement of the lower fixed jaw 45 engaging against a pin 65, which extends diametrically through the shaft 11 and projects from the side thereof.

Assuming that the effective travel of the operating mechanism C is six inches longitudinally of the shaft 11 during downward movement of the mechanism C upon the shaft 11, whereby the pin 61 of the lock 70 clutch mechanism 43 will travel for six inches in its groove 14. Since the pitch of the spiral groove is one circumference in twelve inches, it is obvious that a six inch travel of the mechanism C will effect a one 75 half circumferential rotation of the shaft 11, or through 180°. The return movement of the mechanism C, as above described will lock the lower clutch mechanism 44 and the pins 62 will travel in their groove 15 for six 80 inches longitudinally of the shaft 11. As the pitch of the groove 15 is one circumferential winding in eight inches longitudinally of the shaft 11, it is obvious that a six inch travel will result in a movement of the 85 shaft through 270°, or for a three quarter circumferential movement. Thus, the down movement of the mechanism C rotates the improved valve grinding tool A through a less angular movement than the opposite rotary movement effected by linear movement of the mechanism C upwardly upon the shaft 11.

The outer surface or circumference of the shaft 11 has been shown in diagrammatic or developed form in Figures 5 and 6, and whereon are respectively shown the grooves 14 and 15 and their relative inclination or pitch. The distance *a*, as indicated in Figure 5, is that distance which the pins 61 of the clutch mechanism 43 will travel in the groove 14, as the operating mechanism C is moved downwardly in order to effect a rotation of the shaft 11, which may be appropriately designated by the character *a'*. As 100 the distance *b*, as indicated in Figure 6, the pins 62 of the clutch mechanism 44 will travel for the distance *b* which is the same distance as the length defined by letter *a*. Due to the variation in pitches of the grooves 14 and 15, it 105 can readily be seen that travel of the mechanism C upwardly in the groove 15 will effect an opposite rotary travel from that above described, which may be appropriately represented in Figure 6 by character *b'*. Thus it can readily be seen that the angular 110 movement of the shaft 11 effected by a linear movement of the mechanism C downwardly upon the shaft 11 will be less than the angular movement of the shaft 11 in opposite 115 direction to the prior angular movement, and which larger angular movement is effected by upward movement of the operating mechanism C upon the shaft 11.

Any pitch ratio of the grooves 14 and 15 120

may be provided in the shaft 11, and if desired, diametrically opposite spiral grooves of similar formation may be provided for each of the clutch mechanisms 43 and 44, 5 since it is thought that less binding will result with such arrangement. Spirally formed threads of different pitch may be provided upon the shaft 11 in lieu of the grooves 14 and 15, which might be constructed to operate effectively with the clutch mechanisms 43 and 44. It is to be clearly understood that the principle of this invention contemplates the provision of spiral grooves or threads, or any similar arrangement to effect oscillatory movement of the shaft 11 over varying paths of travel.

From the foregoing, it can be seen that a device for valve grinding has been provided which is positive and effective in securing 20 the desired movements for valve grinding operations. The working of the operating means C upon the shaft 11 does not contemplate the provision of a lost motion to effect the desired result, namely, the oscillation of 25 the shaft 11 over varying angular movements, since any linear movement of the means C on the shaft 11 will produce a rotary movement of the shaft 11 according to the direction in which the means C is 30 being moved longitudinally of the shaft 11.

Various changes in the shape, size and arrangement of parts may be made to the form of the improved valve grinding tool, without departing from the spirit of the invention or the scope of the claims.

I claim:

1. In a grinding tool for producing reverse rotary motions, a shaft having grooves provided therein of different pitches, and a 40 handle mechanism reciprocably mounted on said shaft including independent clutch mechanisms slidably upon the shaft engaging in different grooves of the same, whereby upon reciprocation of the handle mechanism, the clutch mechanisms will automatically engage and disengage to cooperate with the grooves in said shaft to effect rotary movement of the shaft in different directions at different speed ratios.
2. In a grinding tool, a shaft having grooves spirally positioned thereon of different pitches, and reciprocating means cooperating with said shaft grooves and adapted for engagement in one of them to impart 50 rotary movement to the shaft during linear movement of the reciprocating means in one direction, and adapted for automatic engagement in a second groove to impart rotary movement to the shaft in an opposite direction during linear travel of the reciprocating means in a linear direction opposite to said first mentioned linear direction.
3. In a grinding tool for producing reverse rotary motions, a shaft having a plu-

rality of grooves therein of different pitches, 65 and a handle mechanism reciprocably mounted upon said shaft, including a casing and a pair of clutch members slidably cooperating in said casing, each including pins projecting into different grooves of the 70 shaft, said handle mechanism when moved in one direction longitudinally of the shaft adapted to have one clutch mechanism held in locked manner with the handle mechanism to impart rotary movement to the 75 shaft, and when moved in an opposite direction longitudinally of the shaft, adapted to have the other clutch mechanism locked relatively within the handle mechanism to impart opposite rotary movement to the shaft, 80 and whereby the opposite rotary movements of the shaft will be of unequal angular travel.

4. In a grinding tool for producing reverse rotary motions, a shaft having a plurality of grooves therein of different pitches, 85 a hand engaging member swivelly mounted upon one end of said shaft, a bit element mounted on the other end of said shaft, and a handle mechanism including a pair of clutch devices mounted in the opposite ends thereof slidably mounted upon said shaft, 90 each of said clutch devices having pins projecting into a spiral groove of said shaft, so that when said hand mechanism is reciprocated on the shaft in one direction, one of said clutch mechanisms will be locked with the handle mechanism and the other clutch mechanism automatically disengaged with 95 the handle mechanism to effect rotary movement of the shaft in one direction, said handle mechanism when moved longitudinally of the shaft in a second direction adapted 100 for having said clutch mechanisms automatically shift to effect a rotary movement of the shaft in opposite direction.

5. In a grinding tool for producing reverse rotary motions, the combination of a shaft having a plurality of grooves spirally positioned therein at different inclinations, a 110 hand engaging operating mechanism reciprocably mounted on said shaft including an outer casing having fixed jaws positioned upon the upper and lower ends thereof, sliding jaws mounted in said casing for cooperation with the fixed jaws, and pins carried by said sliding jaws engaging in different spiral grooves.

6. A valve grinding tool comprising a shaft having a pair of grooves spirally positioned thereon at different pitches, and an operating mechanism slidably longitudinally of the shaft, including independent mechanisms for cooperative association in the grooves of said shaft, whereby during downward movement of the operating mechanism upon the shaft, the same will impart a rotary movement to the latter of less angular

travel than the rotary movement imparted to the shaft by upward movement of the operating mechanism upon the shaft.

7. In a grinding tool for producing reverse rotary motions a shaft having a pair of spiral grooves longitudinally disposed therein in adjacent relation and at different pitches, and means reciprocable on the shaft adapted when moved in one direction on the shaft to engage in one of said grooves for

imparting rotation to the shaft, and moved on the shaft in an opposite direction adapted to slidably engage in the other groove to impart rotation to the shaft in an opposite direction, whereby upon reciprocation of the means for the same length on said shaft in opposite direction said shaft will have imparted thereto different degrees of rotation in opposite directions. 15

GEORGE F. FERRIS.
